UNITED STATES PATENT OFFICE.

FREDERICK A. RUFF, OF ST. CLAIR, MICHIGAN.

WASHING-MACHINE.

SPECIFICATION forming part of Letters Patent No. 326,060, dated September 8, 1885.

Application filed December 19, 1883. (No model.)

To all whom it may concern:

Be it known that I, FREDERICK AUGUST RUFF, of St. Clair, in the county of St. Clair and State of Michigan, have invented new and useful Improvements in Washing-Machines; and I hereby declare that the following is a full, clear, and exact description thereof, reference being had to the accompanying drawings, which form a part of this specification.

This invention relates to certain new and useful improvements in the construction of "washing-machines," as they are ordinarily termed.

The invention consists in the construction of the various parts and their novel combination and arrangement, as more fully hereinafter described.

Figure 1 is a longitudinal sectional view. Fig. 2 is a transverse sectional view. Fig. 3 is a detail of a portion of the wash-board bottom enlarged.

In the accompanying drawings, which form a part of this specification, A represents the rectangular tub supported on suitable legs, B, and it may be provided with any suitable device for drawing off the water, if preferred.

C are coiled or other springs, preferably made of non-corrosive metal to support the corrugated zinc wash-board D, which is secured in a proper frame of a size to loosely fit the tub. At various places this wash-board is perforated, preferably in the lowest portion of the corrugations, as shown at b.

E is a frame of a shorter length than the length of the tub, and it is supported upon the arms F, which are pivotally hung at the top of the tub, and one pair of these arms are connected together by a yoke, G, the free ends of which are connected by a bar, H, which forms a handle, the parts being so connected and supported that the frame E is given a reciprocating motion by the vibration of the handle. To one side of this frame E is hinged the rubber proper, J. This rubber is composed of a series of slats connected together in pairs by a suitable cross bar or bars, K. These slats on their adjacent sides are inclined inversely from each other. If preferred, suitable stops, a, may be secured to the walls of the tub to limit the upward action of the springs upon the wash-board; but these are un-

necessary, as under the ordinary operation of the machine the pressure on the frame E, caused by the force of the operator on the handle H, will prevent the wash-board from rising, so that if it is desired to examine the clothes with the wash-board depressed it is only necessary to bring the arms F in a vertical position, when the frame E, resting on the frame D, holds the latter in place, when the rubber J may be lifted or swung upward, and the clothes examined or more clothes put in as desired.

In practice, the water is placed in the tub, and preferably such water should not be more than sufficient to fill the tub to the height of the wash-board. The rubber proper is then tilted up, as shown in the drawings, and the garments to be acted upon are then spread upon such wash-board, and the rubber returned to its former position, and its free end secured to the frame opposite the hinged side by a button or other well-known detent. Now the operator by vibrating the handle reciprocates the frame, carrying the rubber over the clothes, the springs below tending to force the wash-board upward and against the downward pressure of the rubber in its reciprocating motion, which is somewhat curvilinear under the action of the crank-arms which carry it. This motion presents one of each pair of slats of the rubber with its lower sharpened edge to the garments, thereby scraping them, while the fellow slat presents its obtuse angle and presses or squeezes them. This occurs in each reciprocation of the rubber, and as the wash-board gives under this action the water is forced up and through the garments through the perforations heretofore described in the wash-board. When the clothes are thus cleansed, the rubber is tilted out of the way, as shown, when the garments can readily be removed to the wringer, which may be secured to one end of the tub.

I am aware of the Patents Nos. 45,122, 95 63,644, 71,445, and 265,695, and make no claim to the construction shown therein as forming part of my invention.

What I claim as my invention is—

In a washing-machine, the wash-board D, consisting of a rectangular box-like frame provided with a perforated corrugated zinc

bottom, in combination with a frame, E, resting on and traversing over said wash-board frame, and a reciprocating rubber, J, hinged to said frame, and provided with slats extending below the rubber frame into the space inclosed by the wash-board frame, leaving a space between said slats and said perforated

bottom, whereby injury to the clothes or buttons thereon is prevented, substantially as set forth.

FREDERICK A. RUFF.
